UNITED STATES PATENT OFFICE.

ALBERT MEADOWS, OF DETROIT, MICHIGAN, ASSIGNOR TO DETROIT VAPOR STOVE COMPANY, OF DETROIT, MICHIGAN, A CORPORATION OF MICHIGAN.

OVEN-FRONT CONSTRUCTION.

Application filed July 15, 1922. Serial No. 575,346.

To all whom it may concern:

Be it known that I, ALBERT MEADOWS, a citizen of the United States, residing at Detroit, in the county of Wayne and State of Michigan, have invented certain new and useful Improvements in Oven-Front Constructions, of which the following is a specification.

This invention relates to stove construction. The improvement resides in a construction of the oven and broiler oven. It is the object of the invention to afford a strong pressed metal front which is united with the other walls of the oven and broiler oven by a joint having no exposed fastening devices. It is the further object of the invention to provide reinforcing members along the back of the pressed metal oven front which also serve the purpose of clamping the turned in side walls in place. The details of this will more fully appear in the description following.

In the drawings,—

Fig. 1 is a fragmentary front elevation of a stove equipped with my improved front construction.

Fig. 2 is a section taken on the line 2—2 of Fig. 1 with the door omitted.

Fig. 3 is a section taken on the line 3—3 of Fig. 1.

The oven front and broiler oven front comprise a pressed steel channel frame *a* provided with an upper opening for the oven and lower opening for the broiler chamber. This frame is provided with suitable slots *b* through which the hinges (not shown) function. These hinges and the fulcrum blocks *c* which support them are described and claimed in my co-pending application No. 575,345. No claim is made to this construction in the present application. The side walls of the oven are designated *d* and are provided with a jog at *c* to receive the turned back outer edge of the front channel frame, forming a substantially flush joint. The outer portion of the channel frame curves in a long, sweeping curve of considerable radius through an arc of 90°. Coupled with the flush joint already described, this forms a large rounded corner on the sides and top of the stove with an almost invisible joint giving a very clean, pleasing appearance and making the cleaning of the stove easy.

With the doors closed there are no ex-

posed fastening devices whatever. The side walls *d* are turned in at a right angle to form the flanges *e* which are clamped between the angle iron reinforcing bar *f* and the block *c*. This block *c* happens to be the fulcrum block that is described and claimed in application No. 575,345, but obviously as far as stove construction here described and claimed, it might be any ordinary block used for no other purpose. The angle bar *f* is described and claimed in application No. 575,345, as a fixture supporting hinges and springs, but obviously it is used in the structure shown in this application for an entirely different purpose, namely to reinforce the channel frame and pinch the side walls to the block *c*. The hinges and springs might be supported by other parts of the stove.

The stove doors are provided with wings *h* at the bottom of the sides for connection with the hinge arms (not shown) which function through the slots *b* and for covering the stove bolt heads *g* which together with the nuts *i* and *j* securely clamp the reinforcing angle bar *f* to the block *c* and pinch the side wall flanges *e* in place. This forms a concealed fastening when the door is closed.

In place of this construction, along the top a flat reinforcing bar *k* is used and a deeper flange *m* is turned in on the top wall *n* of the oven. This is pinched against the stepped wall of the stove *o* at the outer jamb. The fastening devices, preferably bolts, have their heads *q* welded to the inside of the channel to secure the reinforcing strips *k* to the back of the front frame and pinch the flange *o* between the reinforcing strip and the back of the step of the jamb.

What I claim is:

1. In stove construction, the combination of a front frame including one or more oven openings and having the outside edges of the frame turned backwards, a chamber having a wall meeting said turned back edges in substantially flush relation and concealed fastening devices for uniting said wall to said frame.

2. In stove construction, the combination of a front, comprising a channel-like frame having one or more oven openings and having outer edges turned back through substantially 90°, a chamber having a wall formed with a jog so that the wall meets said

turned back edges of the front frame in substantially flush relation, and means for securing the edge of said wall to the back of the front frame.

- 5 3. In stove construction, the combination of a channel-like front frame having a pair of oven openings and have its edges turned backwards, an oven having one or more walls meeting said turned back edges with
- 10 a jog to provide substantially flush joints, the front edges of said wall turned inwardly and means for anchoring said edges to the back of the front frame in concealed relation.
- 15 4. In stove construction, the combination of an oven front frame, an oven wall turned in behind said frame and fastening devices for removably securing the wall to the frame and permanently secured to the back of the
- 20 frame.
- 5. In stove construction, the combination of an oven front frame, an oven wall having a flange turned in behind the oven frame, and bolts and nuts for securing the flange
- 25 removably to the back of the frame and having some of the fastening members welded to the back of the frame.

6. In stove construction, the combination of an oven front frame, an oven wall having a flange turned in behind the oven frame, a reinforcing bar for also clamping the flange in place, and concealed means for removably securing the reinforcing bar to the back of the oven frame.

7. In a stove construction, the combination of an oven front frame, a wall with a turned in flange turned in behind the frame, a reinforcing bar for also clamping the flange in place, and bolts and nuts some of which are welded to the back of the oven front frame and arranged in concealed relation to clamp the bar and flange to the back of the frame.

8. In stove construction, the combination of an oven front frame, an oven wall having a turned in flange, a block secured behind the frame, a reinforcing bar for clamping the flange to the block, and concealed fastening devices for removably securing the bar to the block and back of the frame and holding the flange between the bar and block.

In testimony whereof I affix my signature
ALBERT MEADOWS.
